UNITED STATES PATENT OFFICE

ANDREW A. KERMIS, OF ROCHESTER, NEW YORK, ASSIGNOR TO KERMIS TENT & AWNING CO., OF ROCHESTER, NEW YORK, A FIRM COMPOSED OF ANDREW A. KERMIS AND BERNARD MEYERING

FUNERAL FURNITURE

Application filed September 24, 1925. Serial No. 58,438.

The present invention relates to funeral furniture and an object thereof is to provide an ornamental article of furniture which may be used in connection with the casket for the purpose of holding cards, such as cards of condolences or sympathy, or mass cards. Another object of the invention is to provide in connection with the card holder, a holder for a sheet of material on which some word or expression in keeping with the occasion is arranged.

To these and other ends, the invention consists of certain parts and combinations of parts, all of which will be hereinafter described, the novel features being pointed out in the appended claims.

In the drawings:

Fig. 1 is a perspective view of a casket showing the article of furniture in position on the casket;

Fig. 2 is a transverse section through the article; and

Fig. 3 is a longitudinal section through the rear upright portion.

Referring more particularly to the drawings, 1 indicates the casket and 2 the cover therefor. Arranged to extend longitudinally of the casket is a member 3 which is suitably upholstered and covered with a fabric 4 which will blend with the colors of the casket. About the upper part of this fabric straps of tape 5 are secured at 6 to their ends and between their ends are free. Beneath the tapes 5, which blend in colors with the colors of the fabric 4, the cards are inserted by those calling to view the remains. Hinged to the card holding member 3 at 7 is a back piece 8 which is upholstered and covered with a fabric 9 having the color of the fabric 4. At one end of this back piece and transversely thereof, is a ribbon or strip 10 which is fastened at its ends, but is free between its ends. Under this ribbon may be fastened any type of device, such, for instance, as a crucifix. This back member 8 has a pocket or depression 11 in the front face thereof in which a removable strip 12 is secured by screws 13. The face of this strip may be covered by a fabric 14 on which may be printed an inscription or word suitable to the occasion. As this strip

12 is removable, the inscription on this fabric 14 may be changed to meet the desires of those holding the funeral. By hinging the members 3 and 8 together at 7, they may be folded one upon the other to protect the faces of the pieces when not in use, and, at the same time, to make it possible to ship or pack the furniture in compact form. If desired, the card holder may have forward extensions 15 at opposite ends to serve as a support for statues, figures, or candle holders.

This invention gives an effective means for securing mass, sympathy or condolence cards, and, at the same time, provides means for supporting articles in position about the casket. Provision is also made for the display of a suitable word or expression.

What I claim as my invention and desire to secure by Letters Patent is:

1. Funeral furniture comprising an elongated shelf adapted to rest on the inside of the open cover of a casket and having a smooth top surface and card securing strips extending transversely of the shelf and secured at opposite sides of the shelf, those portions of the strips between the secured ends being free of the shelf so that cards may be passed under them to project from both sides of the strips.

2. Funeral furniture comprising an elongated horizontally arranged shelf, card holding means for holding cards on the top surface of the shelf, a back piece extending upwardly from the rear edge of the shelf and substantially coextensive in length with the latter, and means for holding objects to the front face of the back piece.

3. Funeral furniture comprising an elongated member adapted to be arranged on the inside of the cover of an open casket having a substantially flat top surface and strips of tape extending transversely of the upper surface, secured at opposite sides of the surface, but free of said surface between the secured portions so that cards may be held between the surface and the strips, the ends of said member being free of the strips and formed with projections for supporting objects used at funerals, an elongated back member projecting upwardly at the rear edge of the first

mentioned elongated member and provided with a substantially flat front face, and a strip of tape extending transversely of the back member over the front face of the latter, said tape being free from said front face so that an article may be held between the surface and the tape.

4. Funeral furniture comprising an elongated member adapted to be arranged on the inside of the cover of an open casket having a substantially flat top surface and strips of tape extending transversely of the upper surface, secured at opposite sides of the surface, but free of said surface between the secured portions so that cards may be held between the surface and the strips, an elongated back member projecting upwardly at the rear edge of the first mentioned elongated member and having a front face provided with a pocket, and an expression containing member removably secured in said pocket.

5. Funeral furniture comprising an elongated shelf adapted to rest on the inside of the open cover of a casket, and having its free ends formed with projections for supporting objects used at funerals, a back piece hinged to the rear of the shelf and projecting above its upper surface, and means for holding an object to the front face of the back piece.
